UNITED STATES PATENT OFFICE.

JAMES S. BAKER, OF FORT SMITH, ARKANSAS.

PASTING-TABLE FOR PAPER-HANGERS.

1,290,046.

Specification of Letters Patent.

Patented Jan. 7, 1919.

Application filed February 6, 1918. Serial No. 215,626.

To all whom it may concern:

Be it known that I, JAMES S. BAKER, a citizen of the United States, residing at Fort Smith, in the county of Sebastian, State of Arkansas, have invented a new and useful Pasting-Table for Paper-Hangers; and I do hereby declare the following to be a full, clear, and exact description of the invention, such as will enable others skilled in the art to 10 which it appertains to make and use the same.

This invention relates to an improved paper-hanger's pasting table, and one of the objects of the invention is to provide a table 15 of this kind for facilitating the unreeling of the rolls of paper, and measuring the sizes of pieces to be cut.

A further object of the invention is to provide a pasting table, which is easily and 20 conveniently collapsible, whereby the same may be stored in a compact small compass.

A further object of the invention is to provide a table of this kind, which is adjustable for facilitating the support of wall 25 paper of different widths.

In practical fields the details of construction may necessitate alterations falling within the scope of what is claimed.

The invention comprises further features 30 and combination of parts as hereinafter set forth shown in the drawings and claimed.

In the drawings:—

Figure 1 is a view in perspective of the improved paper hanger's pasting table constructed in accordance with the invention.

Fig. 2 is a sectional view on line 2—2 of Fig. 1.

Fig. 3 is a longitudinal sectional view on line 3—3 of Fig. 1.

Fig. 4 is a transverse sectional view on line 4—4 of Fig. 1.

Fig. 5 is an end elevation of one end of the table.

Referring more especially to the drawings, 45 1 designates the top board or table top, which comprises the two sections 2 and 3, their longitudinal adjacent edges being hingedly connected as at 4, so that said sections may be folded one upon the other in a 50 small compass. The under faces of said sections near the opposite ends of the table top are provided with transversely arranged depressions or sockets 5 to be engaged by the extension dowels 6 of the upper end of the 55 legs 7, thereby holding the legs rigid and

supporting the table top. The legs 7 are provided with lateral extension members 8 rectangular in cross section, and arranged under the table top and spaced therefrom and between the legs is a rectangular frame 60 9. This frame 9 comprises the longitudinal side bars 10 and the end pieces 11. These end pieces 11 each consist of overlapping sections 12. Where these sections 12 overlap, they have their adjacent portions cutaway 65 as shown at 13, there being registering slots 14, to receive the bolts 15, to hold the end sections in different adjusted positions, according to the width of paper to be supported, and finally applied with paste. The 70 table top is not designed to be extended or made wider. In other words the table top is of its maximum width; but owing to the several transversely arranged depressions or sockets 5, the legs may be adjusted so that 75 the pins 6 may engage any of the sockets so that the legs may be arranged closer or farther apart particularly since the sections 12 are extensible. Furthermore when the legs are arranged closer together, shorter 80 rolls may be employed according to the different widths of paper to be hung. The end sections 12 are provided with U-shaped grooves 16 and 17. These grooves receive correspondingly shaped tongues 18 and 19 85 of the plates 20 and 21 respectively, so that the width of the frame 9 may be easily adjusted according to the adjustment of the legs 7. The sheet metal plate 20 has a curved portion 22 for the support of a roll 90 of wall paper 23, and hinged at 24 to the curved part 22 is a curved cover part 25, to arch over the roll of wall paper, to retain the same in place. A supporting cord, wire, or the like 26 has one end attached at 27 to 95 the plate 21, and is passed back and forth through and from the apertures 28 of said plates 20 and 21 and has its other end attached at 28 to the plate 20. This cord or wire constitutes means to support the wall 100 paper as it is unreeled from the roll. The longitudinal side bars 10 of the frame 9 have secured to them as at 30 plates 31, which are provided with extension parts 32 having sockets 33, which are rectangular and designed for the reception of the extension members 8 of the legs, thereby supporting said frame 9. One of the longitudinal side bars 9 has a guide rod 34 carried thereby, and rockably mounted upon this rod is a 110

member 35 provided with a cutting end 36 and a hand piece 37. The sheet metal plate 21 at its ends is provided with upturned ears 38 having notches 39, to receive the pintles 40 of the roller 41. Plates 42 are secured at 43, one to one end of each section of the table top. These plates 42 have ears 44, to receive the pintles 45 of the roller 46. A suitable rod 47 has at one end a universal connection as at 48 to a plate 49, which is secured at 50 to one of the ends of one of the sections of the table top, near the longitudinal edge of the top. The other end of the rod 47 has a right angle end portion 51, whereby the rod may be manipulated. A heavy steel wire bail member 52 has its end portions 53 pivotally mounted in the arched plates 54 of the under face of the table top, whereby this bail member may swing downwardly in engagement with the wall paper when supported by the wire or cord 26 to hold the paper in place. When the table is collapsed, and the table top folded, the bail member is swung up in order to engage the hook 55, there being sufficient spring in the longitudinal part of the bail to spring over the hook. One of the longitudinal outer edge portions of the section 3 of the table top has a scale 56 in feet, while one of the longitudinal side bars 10 of the frame 9 is provided with a similar scale 57 in feet. The frame 9 is spaced substantially a foot below the table top, so that the paper passing from the roll 41 to the roll 46 will approximately measure 1 foot. In pasting wall paper, the roll is placed in the curved part 22 of the plate 20, the paper is unreeled and arranged along the supporting cord 26, under the roller 41, and over the roller 46, after which the weighted rod 47 is placed over the paper to hold the same flat and stretched. The bail member is allowed to swing downwardly to hold the paper in contact with the cord 26. The member 35 is then moved along its rod, until the length of the piece of paper desired is measured, and then the member 35 is actuated so that the cutting part 36 will nick the paper, indicating where the paper should be cut when that part of the paper reaches the upper surface of the table top. These steps of operation are continued until the desired num-

ber of pieces of paper have been supplied with paste and cut.

The invention having been set forth what is claimed as new and useful is:—

1. A paper hanger's pasting table, comprising a table top consisting of a pair of longitudinal sections edgewise hingedly united, supporting legs having detachable connections with the table top, and a frame spaced below the top and having detachable connections with said legs, a paper roll supporting means at one end of said frame, one end of said frame and one end of the table top having rollers over which the wall paper passes, and supporting means connecting the opposite ends of said frame.

2. In a paper hanger's pasting table, a table top, detachable legs therefor, an elongated rectangular frame detachably connected to said legs and being spaced below the top, said frame being adjustable transversely, a roll paper supporting means at one end of the frame, one end of the frame and one end of the top having rollers over which the wall paper passes, and a bail member pivoted to the under part of the top to hold the paper on said frame.

3. In a paper hanger's pasting table, a table top, supporting legs adjustable transversely of the top and being detachably connected thereto, an elongated rectangular frame detachably connected to said legs and spaced below the top, said frame having a pair of sections adjustably connected transversely, a roll paper supporting device having a detachable slide connection with one end of said frame, one end of the frame and one end of the table top having rollers over which the wall paper passes to engage the top, a weight at one end of the top to engage the paper, and a bail member pivotally suspended from the top to engage the paper on the frame, and a supporting wire connecting the opposite ends of the frame.

In testimony whereof I have signed my name to this specification in the presence of two subscribing witnesses.

JAMES S. BAKER.
